HOUSING FOR AN EVAPORATIVE AIR COOLER

Alfred B. Christopher, Kern, Calif.
(2150 Orange St., Rosamond, Calif. 93560)

Filed May 9, 1967, Ser. No. 7,040

Term of patent 14 years

(Cl. D23—141)

FIGURE 1 is a rear perspective view showing my new design for a housing for an evaporative air cooler;

FIGURE 2 is a front perspective view of the housing;

FIGURE 3 is a view similar to that shown in FIGURE 2 illustrating the baffle plate in its extended position;

FIGURE 4 is a rear elevational view of the housing shown in FIGURE 1;

FIGURE 5 is a front elevational view thereof;

FIGURE 6 is an elevational view as taken from one side thereof;

FIGURE 7 is a top plan view thereof;

FIGURE 8 is a bottom plan view thereof; and

FIGURE 9 is a front elevational view thereof showing the baffle plate in its extended position.

The cross-hatched pattern fragmentarily shown throughout the figures is representative of a conventional grille pattern and is understood to be continuous throughout the areas so shaded.

I claim:

The ornamental design for a housing for an evaporative air cooler, substantially as shown and described.
